PIEZOELECTRIC CRYSTAL HOLDER

Richard S. Bailey, Baltimore, Md., assignor to
 Bendix Aviation Corporation, South Bend, Ind.,
 a corporation of Delaware

Application April 20, 1942, Serial No. 439,671

6 Claims. (Cl. 171—327)

This invention relates to the mounting of piezo-electric crystals and more particularly to a crystal holder of improved appearance and enhanced utility.

As is well known, the primary use of piezo-electric quartz crystals is for the control of the frequency of transmitters requiring a high order of stability. In such transmitters, the operating frequency can usually only be changed by inserting a new crystal into the crystal oscillator circuit, and during operation, any change required is generally made by the adjustment of a selector switch which inserts a selected crystal into the desired circuit. However, in military aircraft equipment, it is often desirable or necessary to be able to rapidly change the channel frequencies available, this change being made at the operating base for the aircraft; and this latter change requires the physical insertion of new crystals or crystal assemblies into suitable receptacles in the equipment. Among the previously available holders, those which may be readily interchanged without unsoldering or unscrewing connections, as by merely snapping into place have been excessively bulky, and those of minimum bulk have been inconvenient to interchange.

One of the principal objects of this invention is to provide a piezo-electric crystal assembly occupying a minimum of space and convenient to interchange.

Another object of this invention is to provide a new and novel piezo-electric crystal assembly which is adapted for mounting in low cost and widely available fuse clips.

Still another object of this invention is to provide a new and novel piezo-electric crystal assembly in which the crystal may be visually inspected without removal from said assembly.

The above objects and advantages of the invention are accomplished by mounting a crystal provided with metallic films on two sides so that the crystal is held by two spring clamps, each clamp being secured to a cylindrically shaped metallic end-cap one of which, in turn, fits over each end of a transparent cylindrical enclosure. Each of the clamps mentioned makes contact to only one of the conducting films, and connection to the crystal controlled circuit is established through the metallic end-caps.

Other objects and advantages of the invention will in part be disclosed and in part be obvious when the following specification is read in conjunction with the drawing in which:

Figure 1 is a side view of the completed holder, with the crystal in place.

Figure 2 is a view in perspective of the completed holder with the crystal in place, together with a suitable clip mounting assembly.

Referring to Figure 1, the crystal 1 is provided with the conductive coatings 2 and 3 on either side. At its left end, the crystal 1 is held by the spring clamp 4 which is of conducting material and makes contact with the conductive film 2, conductive film 3 being removed in the region contacted by the clamp 4. At its right end, the crystal 1 is held by the spring clamp 5, also of conducting material which makes contact with the conductive film 3, conductive film 2 being removed in the region contacted by the clamp 5. The clamp 4 is carried on a cylindrical mounting support 6, of which a portion 7 is reduced in diameter. The reduced portion 7 of the mounting support extends through the aperture 8 in the end-cap 9 and the projecting segment is peened over as at 10 to secure the clamp assembly in the end-cap. Where a hermetic seal is desired, the reduced portion 7 may be sweated in place, thus eliminating the need for the peening operation. The spring clamp 5 is similarly mounted to the end-cap 11. The enclosure surrounding the crystal 1 is completed by the cylindrically shaped glass or transparent plastic container 12, the end-caps 9 and 11 being slipped over the opposite ends of the cylinder thus defined. The end-caps 30 may be cemented or otherwise suitably secured to the container of body 12 to maintain them in place, the care and method used in this operation being dependent on the excellence of seal required. Hermetically sealed containers may be 35 evacuated or filled with any desired fluid or gas.

The perspective view of Figure 2 shows the neat and attractive appearance of the completely assembled crystal and holder, with the end caps 9 and 11 in place at opposite ends of the cylindrical enclosure 12 and the spring clamps 5 and 4 (not shown) supporting the crystal 1 and making contact to the conductive coatings 3 and 2 respectively. This view shows the crystal and holder just after being removed from a cooperating holder comprising the fuse mounting clips 13 and 14 secured by the rivets 15 and 16 to the mounting base 17, which is of insulating material. Connecting lugs 18 and 19 inserted under the rivet heads provide a convenient means for wiring the crystal assembly into the operating circuit.

The end-caps 9 and 11 are at once the means of establishing electrical connection to the crystal electrodes and supporting the assembly. The necessary electrical connections to the crystal controlled circuit are preferably brought out to

a pair of spaced metallic spring clips in a mounting of the general type just described, and the completed assembly is then snapped into place in the spring clips in the usual manner. When the necessity arises for changing the operating frequency of the crystal controlled equipment, it is necessary merely to snap the old assembly out and insert the new one in its place, the entire operation consuming but a few seconds. At any time that it may be deemed advisable the crystal element may be visually inspected to determine whether it is cracked or broken without removing the holder and crystal assembly from the supporting clips and without removing the crystal from the holder itself. It is readily observed that the entire volume occupied by the crystal and holder is far less than that of other apparatus for the same purpose in present use.

While I have described the use of a transparent enclosure, it is evident that the mechanical advantage of rapid interchangeability will be retained upon the substitution of an opaque substance for this purpose, only the advantage of facile visual inspection being lost. The conductive films on the surface of the crystal may be found thereon by sputtering, or plating, or may consist simply of metallic foil cemented in place. The tubular crystal enclosure need not necessarily be of circular cross section, but may exhibit a cross section having the form of any polygon such as a rectangle, pentagon, hexagon, etc. as desired, the end caps being modified accordingly.

It will be obvious that many changes and modifications may be made in the invention without departing from the spirit thereof as expressed in the foregoing description and in the appended claims.

I claim:

1. In combination with a plate of piezo-electric material having two operatively associated conducting electrodes, a tubular enclosure of insulating material surrounding said plate, a conducting end-cap at each end of said tubular enclosure, and clamping means carried by each of said end-caps, said plate being secured by said clamping means, and each of said clamping means also making electrical contact with one of said conducting electrodes.

2. In combination with a plate of piezo-electric material having two operatively associated conducting electrodes, a tubular enclosure of insulating material surrounding said plate, a conducting end-cap at each end of said tubular enclosure,

and spring clamping means secured to each of said end-caps, said plate being mounted at opposite ends in said clamping means, said clamping means also making electrical contact with one of said conducting electrodes.

3. In combination with a plate of piezo-electric material having two operatively associated conducting electrodes, a tubular enclosure of insulating material surrounding said plate, a cylindrically shaped conducting end-cap slipped over each end of said tubular enclosure, and spring clamping means secured to each of said end-caps, said plate being mounted at opposite ends in said clamping means, said clamping means also making electrical contact with one of said conducting electrodes.

4. In combination with a plate of piezo-electric material having two operatively associated conducting electrodes, a tubular enclosure of transparent insulating material surrounding said plate, a conducting end-cap at each end of said tubular enclosure, and clamping means carried by each of said end-caps, said plate being secured by said clamping means, and each of said clamping means also making electrical contact with one of said conducting electrodes.

5. In combination with a plate of piezo-electric material having two operatively associated conducting electrodes, a tubular enclosure of insulating material surrounding said plate, the axis of said tubular enclosure being substantially parallel with the plane of said plate, a conducting end-cap at each end of said tubular enclosure, and clamping means carried by each of said end-caps, said plate being secured by said clamping means, and each of said clamping means also making electrical contact with one of said conducting electrodes.

6. In combination with a plate of piezo-electric material having two operatively associated conducting electrodes, a tubular enclosure of transparent insulating material surrounding said plate, the axis of said tubular enclosure being substantially parallel with the plane of said plate, a cylindrically shaped end-cap having a central aperture slipped over each of said tubular enclosure and cemented in place, and a spring clamp mounted in each of said central apertures of said end-caps, said plate being held in place between the clamping members of said spring clamp, each of said clamping members also making electrical contact with one of said conducting electrodes.

RICHARD S. BAILEY.
